United States Patent Office.

JOHN H. DAVEY, OF ROCKFORD ILLINOIS.

Letters Patent No. 79,450, dated June 30, 1868.

IMPROVEMENT IN CULTIVATOR.

The Schedule referred to in these Letters Patent and making part of the same.

TO WHOM IT MAY CONCERN:

Be it known that I, JOHN H. DAVEY, of Rockford, in the county of Winnebago, and State of Illinois, have invented a new and improved Cultivator; and I do hereby declare that the following is a full, clear, and exact description of the construction and operation of the same, reference being had to the annexed drawings, making a part of the specification, in which—

Figure 1 represents a top view.

Figure 2 represents a vertical sectional view.

In both figures—

A is the axle-tree.

B B, a frame securely fastened to axle-tree.

C C, tooth-frame, suspended from frame B B by

D D, standards attached to frame C C, and pierced at different parts, d d, so that the height of the tooth-frame may be regulated.

c c e, sockets for teeth.

E E, pins to fasten the standards to frame B B.

F F, chains connecting forward end of tooth-frame with axle-tree.

G G G, teeth of cultivator.

g g g, rods connecting teeth with frame.

H, standard attached to rear bar of upper frame, mortised at upper end to receive K.

I, standard attached to axle-tree.

K, lever, having its fulcrum in upper part of standard H, and playing through standard I.

K', chain connecting lever with tooth-frame.

L L, wheels.

M, pole or tongue.

N, driver's seat, fastened to axle-tree.

To enable others skilled in the art to make and use my invention, I will proceed to describe its construction and operation:

I first make my wheels, L L, and connect them by a strong axle-tree, and attach to it a pole or tongue for draught, and a driver's seat, substantially as in the drawing. To this, on the upper surface, firmly attach a frame, B B B B, substantially of the shape and proportions represented in the drawing. I then make another frame, C C C C, substantially as represented, and in sockets c c e insert the upper end of the rods g g g of the teeth, which are so arranged that the teeth in the fore bar of the frame will be opposite the middle of the space between the hinder teeth.

This frame I fasten, by chain F F, to the rear side of the axle-tree A. The after part of it is suspended from the upper frame by pins E E, which pass through the ends of the upper frame, and through the standards D D, and are easily drawn out. Each standard is pierced at different points, so that the tooth-frame may be raised or lowered at pleasure, thus regulating the depth at which the teeth will cut into the earth. I also suspend the tooth-frame by a chain, K', to the end of a lever, K, arranged as in the drawings, the front end of which is near the driver's seat, so that he may press it down when occasion requires, taking the teeth out of the earth, and again, by letting it go, returning the teeth to the earth, into which they will be forced by the forward movement of the cultivator.

The teeth I make of the shape of a diamond, or of an ellipse, with the lower end drawn out to a point.

The advantages I claim for my invention are, first, its extreme simplicity, which makes it inexpensive, and not liable to get out of order; second, the ease with which it may be backed, as it is not necessary to lift the teeth from the ground, as by its construction they yield to the backward motion; third, the readiness with which it may be turned, as the teeth may easily be raised; fourth, by the shape of the teeth, and the rods connected

with them, any obstruction will be easily thrown aside, or, if too firm to be moved, will gently press the teeth to one side, instead of breaking them; fifth, the ease with which it is managed by the driver, who may control it without leaving his seat; the reins may be fastened to the front bar of the upper frame, when not necessarily in his hands; sixth, the facility with which the depth of cultivation may be regulated, by means of the standard D D and pins E E.

Having now explained its construction and operation, I will proceed to state what I claim as my invention, and desire to secure by Letters Patent.

I claim the frames B and C, the standards D D, pins E, the chains F F, the lever K, the chain K', all constructed, combined, and operating substantially in the manner and for the purposes set forth.

JOHN H. DAVEY.
